(57) **CLAIM**

The ornamental design for a quick release equipment mount as shown and described.

DESCRIPTION

FIG. 1 is a front, top, right isometric view of a quick release equipment mount according to my new design.

FIG. 2 is a back, bottom, left isometric view thereof.

FIG. 3 is a top plan view thereof.

FIG. 4 is a bottom plan view thereof.

FIG. 5 is a front plan view thereof.

FIG. 6 is a back plan view thereof; and,

FIG. 7 is a left side plan view thereof, the right side plan view being a mirror image thereof.

Shading lines are used to show solid material and are not intended to indicate surface decoration.
